UNITED STATES PATENT OFFICE.

WILLIAM PENTE, OF CHICAGO, ILLINOIS.

BOX.

1,250,348.

Specification of Letters Patent. Patented Dec. 18, 1917.

Application filed November 8, 1915. Serial No. 60,435.

To all whom it may concern:

Be it known that I, WILLIAM PENTE, a citizen of the United States, residing at Chicago, in the county of Cook and State of Illinois, have invented a certain new and useful Improvement in Boxes, of which the following is a full, clear, concise, and exact description, reference being had to the accompanying drawings, forming a part of this specification.

My invention relates to boxes or containers which are shaped as toys so that after performing the function of a container or box for containing goods, such as candies, and such as are likely to be purchased by or for children, may serve thereafter as toys.

The object of the invention is to provide a box or container which can be made at small expense and which will prove attractive, especially to children, for use as a toy.

A further object of the invention is to provide a box or container which may be made of inexpensive material such as paper or card-board and can readily be assembled or folded into proper shape and which will serve a maximum utility as a toy.

The boxes which I shall hereafter describe are employed for containing things which are in demand for children such as candy or the like. These boxes of candy or the like find a very ready sale from the fact that the boxes or containers serve as a very attractive toy during the time, or after, that the box or container serves its function as such.

In the accompanying drawings which form a part of the present specification and in which I have illustrated the manner in which my invention may be carried out—

Figure 1 is an isometric view of a complete box with one end closed up and the other end remaining open;

Fig. 2 is a fragmentary view similar to the view of Fig. 1, showing the interior construction of the box;

Fig. 3 is a similar view of the end showing the one flap folded in and the other flap still open;

Fig. 4 is a similar view showing the first flap open and the second flap closed;

Fig. 5 illustrates the manner of cutting out the blank;

Fig. 6 illustrates an end view of the card or blank for receiving the figure of the animal or other object which is inclosed in the body of the box and serves as a closure for the front of said box;

Fig. 7 illustrates the manner of forming the blank shown in Fig. 5 and consists of a cross-section of a box folded up from the blank, shown in Fig. 5;

Fig. 8 shows the manner of joining the end flaps of two of the boxes together; and

Fig. 9 illustrates a number of the boxes joined together and provided with a paper top to simulate a tent.

The box shown in Fig. 1 consists primarily of a box portion and extensions which form supports for the box to simulate an animal cage. The main box portion 1 comprises a top portion 2, a front 3 and suitable end portions which will be described more in detail later, a back portion 4 and a bottom portion 5. The front portion 3 is cut out or slotted, as shown in Figs. 1 and 5, to simulate a cage, the portions 6 which remain being suitably lithographed or otherwise decorated to simulate the bars of a cage. The openings between the bars 6 are closed by a card 7, having a bottom portion 8, bent at substantially right angles and of a width to cover the bottom side of the cage. The card 7, shown in Fig. 6, has upon its face 9 a pictorial representation of an animal, such for instance, as the lion, shown in Fig. 1. The box shown in Fig. 1 is provided with the supporting tabs 10 decorated to simulate wheels. These tabs are struck out of the material of the bottom of the box, as shown in Fig. 2, thus forming the holes 11 where each tab is stamped out. The tabs 10 thus form a straight downward extension of the front 3. The bottom 5 has a tab or extension 12 which in this case is formed the full length of the bottom and is pasted or otherwise secured to the back 4 of the box. The back 4 extends downward, as shown at 13, for the same distance as the height of the tabs 10, which I term the wheels. Thus the box is provided with supports on each side to hold it up on edge to simulate as much as possible a complete animal cage.

The ends of the box are closed by the following means. The top portion 2 is provided at each end with a narrow flap 14 (see Fig. 1) which folds down to close the upper corners of the box adjacent the portion 2. In the form shown in Figs. 1, 2, 3 and 4 the bottom portion 5 is also provided with narrow flaps 15 similar to the flap 14, shown in Fig. 1 for closing the lower end corners of the box. The front portion 3 is

provided at each end with an end portion 16 (see Figs. 1 and 3) of the proper width to close the end of the box. This end portion 16 is provided with a tab or tongue 17, 5 which when the portion 16 is folded on the outside, is adapted to be inserted in a slot 18 which is cut in the stock of the paper at the point where the back end portions 19 join the back part 4 of the box. This can 10 be seen more clearly in Fig. 5. The end portions 19 which are secured to the back are provided with flaps 20 which are inserted in the open end of the box when the frame is closed in the manner shown in Fig. 1. The 15 end portion 19 extends down the full width of the bottom portion 13 but the end flap 20 extends only the width of the box or container portion. The end portions 19 are provided with tongues 21 formed by slotting 20 the paper. (See Figs. 4 and 5.)

When the box serves as a container for candy or the like the card 7 which is provided with the bottom portion 8 is inserted in the open end of the box after the portion 25 12 is secured to the back 4, the card 7 closing the openings between the bars 6 and the portion 8 closing the openings 11 formed by cutting out the wheels 10. The representation of the animal 22, shown in Fig. 1, is 30 formed upon the face 9 of the card 7 and simulates the animal confined in a cage. The small end tabs 14 and 15 are then folded inwardly, the box being filled with suitable articles. The end portion 19 is then 35 folded over the open end of the box and the flap 20 which is bent along the dotted line is inserted at the edge of the end opening. The portion 16 which is then bent along the dotted line is then folded over the end and 40 the tab or tongue 17 is inserted in the slot 18 thus closing and locking the end of the box.

After the child has emptied the box of its 45 contents the flap 16 with the tongue 17 is folded in first, as shown in Fig. 4, so as to expose the back end portion 19. The flap 20 may then be torn off and the adjacent end flaps 19 of two boxes may be interlocked by means of the tongues 21, as shown in Figs. 8 and 9. The outer back portion may 50 be decorated to simulate a part of a tent and when a number of boxes are joined together as shown in Fig. 9, a paper cone 24 formed of wrapping paper or the like is set upon these boxes to complete the illusion of a 55 circus tent having animal cages arranged around on the inside thereof. This forms a very attractive toy for children.

In Figs. 5 and 7, I have illustrated a 60 modification of the box shown in Fig. 1. In this structure instead of forming the card 7, 8 of a separate piece of material, I have shown the same as forming a continuation of the back portion 4 and have designated the corresponding part as 7', 8'. In- 65 stead of attaching the end tabs 15' to the

bottom portion 5, I have shown them as formed of an extension of the inside bottom portion 8'. The bottom portion 5 is provided with a tongue or tab 12' instead of the full length tab 12. The tab 12' is inserted 70 in a slot 23, as shown in Fig. 7 to close the box at the bottom. The front and back end flaps 16 and 19 are substantially the same as in the prior form of box. The back end portions 19 are provided with the interlocking tongues 21 for joining together 75 a number of boxes.

Where a number of animals or other pictorial representations are desired the same may be secured to extensions of the card 7', 80 all being struck out of the same blank of paper.

I consider that the formation of the picture card integral with one of the end flaps 20 is the equivalent of the structure I have 85 shown and intend that this be considered in the interpretation of the claims.

The manner of joining the end flaps to form a series of connected objects may be varied as the joining flaps may be made 90 like the front end flaps, shown in Fig. 5, and the two similar flaps are then laid over each other with the coöperating tabs 17 inserted in the slots 18.

While I have described the box as being 95 adapted to simulate an animal cage with an animal therein, it is to be understood that any desired object may be simulated, such for instance as a train of cars, a block of houses or similar groups of articles. In the 100 case of a railroad train, the front of the box is cut out to represent the windows of the engine cab or of the coaches and the card 7, 8, within the box presents the figure of the engine driver or of the passengers. The 105 above illustrations are given merely for the sake of showing the application and use of the structure in providing a very attractive toy. While I have described my invention with reference to the details of a particular 110 embodiment, it is not my intention to limit the invention to only such forms as I have shown, as it is apparent that the invention may be applied to different structures and may appear in a variety of forms with such 115 substitutions and modifications as will occur to those skilled in the art, all of which I desire to be included within the scope of the appended claims.

What I claim is:

1. In combination an inclosing or box structure having top, front, bottom and back portions and end portions for closing the same, flaps secured to the body of the box at each end thereof, said flaps having interlocking projections for joining a number of boxes or structures together said interlocking projection holding said flaps flat against each other when so joined together. 125
2. A box blank, having top, front, bot- 130

- tom and back portions, front end flaps and back end flaps, an interlocking slot cut in one of said end flaps for joining a plurality of such structures together, said flaps lying flat against each other when so joined together. 5
3. In combination a box having top, front, bottom, back and end portions for forming an inclosure, said front having perforations therethrough, a card adapted to receive pictorial representations, secured back of said perforations, said back portion having projecting flaps, said flaps lying flat against each other and having slots forming interlocking projections adapted to secure said flaps together. 10
4. In combination a box having top, front, bottom, back and end portions, flaps secured to said box, said flaps having tongues adapted to interlock with tongues of adjacent boxes to connect a group of the same together, said front portion having perforations therethrough and a card adapted to receive pictorial representations, closing the 15 perforations in said front. 20
5. In an article of the class described, top, front, bottom and back portions, folded to form an inclosure, said front portion having perforations therethrough and extensions to 25 form supporting means, said back portion having an extension to form similar supporting means, end flaps secured to said front and back portions for closing the ends of said box and a card in said box to close 30 the perforations through said front, said card being adapted to receive pictorial representations. 35
6. In combination top, front, bottom and back portions, flaps secured to said front 40 and back portions at each end thereof, said front having perforations therethrough and tabs struck up from the bottom portion depending from said front portion, said back portion extending downward the same distance as said tabs, one of said end flaps at 45
- each end of said box having an interlocking tongue and a card in said box for closing the perforations in the front and bottom portions of said box. 50
7. In combination a plurality of boxes secured together to form a polygonal inclosure, said boxes having flaps at each end, said flaps having tongues adapted to interlock with tongues of adjacent boxes to connect the same together and a cover member 55 adapted to form a roof for said inclosure. 8. In combination a plurality of boxes, each box having flaps extending from the ends thereof and forming a continuation of the rear of said box, said flaps having interlocking projections adapted to hold the flaps of adjacent boxes together and to form substantially a continuous wall, said boxes being positioned to form an inclosure and a roof member common to the boxes forming 60 said inclosure. 65
9. A box comprising front, back, top, and bottom portions, said front portion having an opening therethrough adapted to display a picture or the like, said box having a card 70 or flap of substantially the size of said front resting upon the bottom thereof and adapted to close off said opening and to present a picture through said sight opening, said box having suitable end flaps for closing off the 75 end opening to form a complete inclosure. 75
10. A box comprising front, back, top and bottom portions, said front portion having a sight opening therethrough adapted to display a picture or the like back of said opening, suitable end flaps for said box, and a card adapted to be inserted endwise in said box and be placed back of said opening to close said opening, said card being opaque and being of substantially the size of said 80 entire front portion. 85

In witness whereof, I hereunto subscribe my name this 13th day of October, A. D. 1915.

WILLIAM PENTE.
